Taiwan Official Action—105301334—dated Sep. 7, 2016.

Primary Examiner — John Windmuller(74) *Attorney, Agent, or Firm* — Young & Thompson(57) **CLAIM**

The ornamental design for the controller for electronic device, as shown and described.

DESCRIPTION

FIG. 1 is a perspective view of front, bottom and right side of a controller for electronic device showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures depict portions of the article that form no part of the claimed design.

1 Claim, 6 Drawing Sheets(56)
